BELL RINGER FOR LOCOMOTIVES

Application filed November 6, 1928. Serial No. 317,546.

The present invention relates to improvements in bell ringers for locomotives, and has for an object to provide an improved automatic bell ringer in which it will be impracticable to stall the bell or to permit the bell 5 to swing so far as to wind up the bell rope.

Another object of the invention is to provide an improved automatic bell ringer for locomotives in which the ringing of the bell 10 is had by the action of a pneumatic motor coupled to the air line and under the control of a valve in the cab of the engine, such pneumatic motor being so constructed and designed as to avoid the stalling of the bell 15 by cracking the cab air valve, and to provide a compact, efficient motor for ringing the bell at an expenditure of a minimum amount of air pressure.

With the foregoing and other objects in 20 view, the invention will be more fully described hereinafter, and will be more particularly pointed out in the claims appended hereto.

In the drawings, wherein like symbols 25 refer to like or corresponding parts throughout the several views,

Figure 1 is a fragmentary side view of a locomotive boiler with the usual bell and the improved bell ringer coupled thereto.

Figure 2 is a rear view of the bell motor and connections.

Figure 3 is a longitudinal section taken through the motor on an enlarged scale with the parts in an initial position.

Figure 4 is a fragmentary section taken on the line 4—4 in Figure 8 and showing the piston in a subsequent position.

Figure 5 is a fragmentary longitudinal section taken on the line 5—5 in Figure 4.

Figure 6 is a fragmentary longitudinal section similar to Figure 4, but showing the piston and valve in a subsequent position.

Figure 7 is a longitudinal section through 45 the device showing the full right hand position of the piston and valve.

Figure 8 is a cross section taken on the line 8—8 in Figure 4, and

Figure 9 is also a cross section taken on 50 the line 9—9 also in Figure 4.

Referring more particularly to the drawings 10 designates a locomotive boiler and 11 a usual form of locomotive bell having the hanger or yoke 12 provided with the trunnions 13 and 14 mounted in the bearings 15 55 and 16 at the upper ends of the bracket arms 17 and 18. The trunnion 13 is connected at the outer side of the bracket 17 with an arm 19 adapted to receive a bell rope extending to the cab; while the opposite trunnion 14, on the outside of the bracket arm 18 carries a crank 20 secured by a set screw 21 or otherwise to the trunnion 14. The crank pin 22 extends through a bearing sleeve 23 on the cap 24 which is screw-threaded upon the end of the connecting rod 25. A washer is secured over the end of the pin 22 and a cotter pin 27 is passed through the crank pin 22 to secure the washer and the sleeve 23 in place. 70 A lock nut 28 is screwed on the threaded portion of the connecting rod 25 and up against the cap 24.

The connecting rod 25, as shown in Figure 3, terminates in a universal ball 29 mounted in a similarly formed socket 30 in a piston cap 31. The bolt 34 is employed to secure the piston rod 33 to the piston cap 31.

The cap 31 is adapted, in the position of the parts shown in Figure 3, to envelop the extension 35 of the cap or cylinder head 36 80 which is secured as by the bolts 37 or other suitable means to one end of the casing or cylinder 38. A hollow cylindrical valve 39 is shown as fitted to reciprocate within the cylinder or casing 38, such valve having the piston rings 40 at suitable intervals to hold the compression. A piston 41 carried by the piston rod 33 is adapted to reciprocate within the hollow cylindrical valve 39. The closed end of the cylinder is provided with a boss 42 to arrest the movement of the valve 39 in one direction, whereby to leave a slight space between the cylinder end and the valve end; and in like manner a boss 43 is provided upon the inner closed wall of the cylindrical valve to receive the piston 41 and to prevent the piston from closing entirely against said closed wall of the valve 39. A nut 44 is threaded into the opposite end of the valve to retain the piston 41 in place. 100

An oil cup 45 is mounted in the boss 46 in the upper portion of the cylinder or casting 38. The oil cup carries a valve 47 normally held closed by the action of a coil spring 48. In the lower portion of the cylinder are inlet and exhaust ports 49 and 50 respectively. The port 49 is coupled to the air line under control of a valve in the engine cab; while the port 50 may be open to the atmosphere.

The cylindrical valve 39 is provided with three annular channels 51, 52 and 53. These channels open through the periphery of the valve and they are adapted to communicate with the ports 49 and 50, as later described. The channels 51 and 53 connect with a duct 54 which opens into the space within the cylinder valve behind the plunger 41. The annular channel 52 communicates with a duct 55 which opens through the forward portion of the cylindrical valve 39. As shown in Figures 5 and 8 the cylindrical valve 39 is also provided with a longitudinal duct 56 opening through the rear end of the cylindrical valve and communicating with the interior piston space of the cylindrical valve through a port 57 which is located at a forward position where it will be uncovered by the piston 41 only upon movement of the latter in the extreme forward position within the cylindrical valve.

In the operation of the device, the normal position of the parts is shown in Figures 1 and 3. This is the position of rest. When the cab valve is opened, air under pressure is admitted through the port 49, through annular channel 51 which in this position communicates with the port 49, through the duct 54 and behind the plunger or piston 41. The plunger is driven by the air pressure to the position shown in Figures 4 and 5 and against the nut 44. The port 57 is now uncovered by the plunger 41 and air is admitted through this port and the duct 56 to the space in the cylinder 38 behind the floating valve 39, whereby to cause the valve to move to the position, shown in Figure 6.

In this position the air inlet port 49 no longer communicates with the annular channel 51, so that the supply of air is cut off. Moreover, in this position the annular channel 53 is brought into registration with the exhaust port 50 thereby allowing all of the air between the piston and the valve to be evacuated. The bell having been raised through approximately 100 per cent from its central position is now free to swing back and its downward movement causes the piston 41 to push the floating valve 39 back to the starting position, after which the cycle of operations is repeated for the other side, the bell having been carried over the dead center by the force of its swing. As the plunger 41 swings back to the left from the position shown in Figures 5 and 6, the air

before it will have free egress through duct 54, channel 53 and exhaust port 50. When plunger 41 moves to the left of the port 57, the space between the left cylinder head and floating valve is put into communication with the large space between the right cylinder head and valve through the duct 56, port 57, enlarged bore between plunger rod 33 and nut 44. This will allow of a transfer of the air from the left end to the right end of the cylinder as the plunger 41 encounters the valve and moves it from the position shown in Figure 5 to that illustrated in Figure 4. The confined air in the right end of the cylinder may find escape through duct 55, channel 52 and exhaust port 50 when the valve reaches the position indicated in Figure 4.

Should the bell happen to acquire excessive swing, the piston will pull the floating valve 39 to the position, shown in Figure 7, where the annular channel 52 will register with the inlet port 49, permitting air from the supply to act on the forward face of the floating valve 39, thereby retarding the swing and inducing a motion in the opposite direction. This air in the forward portion of the cylinder is exhausted at the end of the downward or rear stroke through the port 50, as shown in Figure 3.

With the improved device, it is impossible to stall the bell by cracking the cab air valve, because, as soon as the piston 41 uncovers the port 57, the floating valve 39 moves to exhaust position thereby releasing all pressure beneath the piston so that the bell is free to swing back.

Moreover, the bell cannot stall up-side-down, nor wind up the bell rope, since the greatest stroke of the piston is less than twice the throw of the crank.

It is obvious that various changes and modifications may be made in the details of construction and design of the above specifically described embodiment of this invention without departing from the spirit thereof, such changes and modifications being restricted only by the scope of the following claims.

What is claimed is:

1. A locomotive bell ringer comprising, in combination with a bell, a plunger rod coupled to the bell, a plunger on the rod, a floating valve movably receiving the plunger and having a closed end and an open end with a cylindrical side wall, a nut to close the open end of the valve, said nut having an enlarged bore about the plunger rod for the passage of air, said side wall of the valve having three annular channels spaced from one another, and including an inlet channel and two exhaust channels, said side wall of the valve also having three angularly separated ducts, one of said ducts communicating with the inlet channel and one of the exhaust channels and

also with the interior space of the valve at the closed end thereof, a second duct communicating with the other exhaust channel and with the space lying beyond the open end of the valve, a third duct opening through the closed end of the valve and having a port at the intermediate portion of the valve communicating with the interior space thereof and opened to opposite sides of the plunger during its movement, and a cylinder for slidably receiving said valve having adjacent spaced inlet and exhaust ports.

2. An improved locomotive bell ringer comprising, in combination with a bell, a cylinder having in its side wall adjacent spaced inlet and exhaust ports, a hollow valve slidably mounted in said cylinder and having a closed and an open end, a plunger slidably mounted within said hollow valve, a plunger rod connected to said plunger and to the bell, means for closing the open end of the valve having a loose fit about the plunger rod for the passage of air, said hollow valve having a plurality of annular channels extending thereabout in axially spaced relation, one of said channels being an inlet channel and adapted to communicate with the inlet port in one position of the valve, a second channel being an exhaust channel and adapted to communication with the exhaust port in one position of the valve, a third channel being also an exhaust channel and adapted to communicate with the exhaust port when the inlet channel is out of register with said inlet port, said valve also having a plurality of longitudinally extending ducts, one of said ducts communicating with the first and third channels and with the interior space of the valve adjacent its closed end, a second duct communicating with the first exhaust channel and opening through the end of the valve adjacent said enclosing means, a third duct opening through the closed end of the valve and having a port opening into the interior space of the valve at an intermediate port and adapted to place the interior valve space in communication with the duct at opposite side of said plunger.

In testimony whereof we affix our signatures.

50 DANIEL S. ELLIS.
CHARLES J. ZUSY.
